UNITED STATES PATENT OFFICE.

SAMUEL H. RANSOM, OF ALBANY, NEW YORK.

DESIGN FOR THE PLATES OF A COOKING-STOVE.

Specification forming part of Design No. 6,729, dated June 24, 1873; application filed April 18, 1873.

To all whom it may concern:

Be it known that I, S. H. RANSOM, of the city of Albany, and county of Albany, and State of New York, have invented a Design for the Plates of a Cook-Stove, of which the following is a specification:

The nature of my design is fully represented in the accompanying engraving, to which reference is made.

A represents the center ornament of large door composed of fancy cross, the arms being of fan-shaped design, with bulb-shaped center ornamentation at their intersection, together with the scroll-work between the arms. B represents the side ornament of large door, (somewhat urn-shaped,) in the contracted part of the door, a combination of the fret-work

base, the intermediate heart-shaped section upon which is carved a rosette, and surmounted by fan-shaped leaf-work. C C C represent ornaments in the center of smaller doors, a combination of oval bulb-shaped center, from which radiate, from top and bottom and sides, the representation of fan-shaped leaves. I do not claim the shape or formation of the moldings.

What I claim as my invention is—

A design for the plates of a cook-stove, substantially in the manner above mentioned.

S. H. RANSOM.
